Patented Dec. 23, 1924.

UNITED STATES PATENT OFFICE.

AMOS N. KNUTSON AND GEORGE H. HACKER, JR., OF BENSON, MINNESOTA.

ATTACHMENT FOR BUTTER PRINTERS.

Application filed May 7, 1923. Serial No. 637,286.

To all whom it may concern:

Be it known that we, AMOS N. KNUTSON and GEORGE H. HACKER, Jr., citizens of the United States, residing at Benson, in the 5 county of Swift, State of Minnesota, have invented certain new and useful Improvements in Attachments for Butter Printers; and we do hereby declare the following to be a full, clear, and exact description of 10 the invention, such as will enable others skilled in the art to which it appertains to make and use the same.

This invention relates to new and useful improvements in butter printing machines, 15 and particularly to attachments therefor.

One object of the invention is to provide a stand or support for a butter printing machine which renders the same readily portable, so that the machine may be moved 20 from place to place, as desired.

Another object is to provide means for attachment to the stand on which the butter, after having been printed, may be wrapped.

A further object is to provide a wrapping 25 stand of the character named which can be removed from the machine stand and folded into a small and compact space.

Other objects and advantages will be apparent from the following description when 30 taken in connection with the accompanying drawing.

In the drawing:

Figure 1 is a side elevation of the invention associated with a butter printing machine.

Figure 2 is a front elevation of the device, the butter printing machine being omitted.

Figure 3 is a front elevation of the stand in folded position.

Figure 4 is a perspective view of one 40 corner of the platform showing the means for holding the legs of the printer, and the casters of the platform.

Referring particularly to the accompanying drawing, 10 represents a horizontally disposed rectangular frame the sides of which are formed from angle strips and rigidly connected at the corners by the triangular plates 11. Each of the plates 11 is formed with a slot 12 which extends on a line bisecting the outer or corner angle of the plate. Disposed on each of the plates 11 is a plate 13, the outer end of which is

turned upwardly and inwardly, as shown at 14, for the reception of the foot 15, of the 55 leg 16, of the butter printing machine 17. A bolt 18 is disposed through each of the plates 13, and through the slot 12, for adjusting the plate 13 to accommodate machines of different sizes. Secured in the 60 corners of the frame 10, directly below the plates 11, are the blocks 19, and carried by each block is a floor engaging caster 20, whereby the frame, and printing machine 65 may be moved from place to place. Carried by one of the side members of the frame 10 are two socket members 21, and removably disposed in these socket members are the lower ends of the legs 22, of the stand 70 which will now be described.

The upper ends of the legs 22 are connected by a transverse bar 23, and carried by this bar are brackets 24, between each pair of which extends a pivot pin 25. Pivotally connected to the intermediate portion 75 of each leg 22 is a transversely inclined arm 26, and connecting the outer ends of these arms is a transverse bar 27. Crossed braces 28 extend between the arms 26, so that the structure will be rigid. Crossed 80 braces 29 are connected to and extend between the legs 22, as clearly seen in Figure 3, of the drawing. The table top is represented at 30, and carried by the lower face of this top, adjacent one end, are the hook 85 members 31 which are pivotally engaged with the pins 25, of the legs 22, whereby the top is capable of being readily folded. Also carried by the lower face of the top 30 are socket members 32 which receive the 90 outer end of the top brace formed by the arms 26 and the transverse bar 27. By slightly raising the table top the brace may be released from the sockets 32, when the brace, as well as the top may be swung 95 downwardly, as seen in Figure 3. The legs 22 are connected to the legs 16, of the printing machine, by means of the braces 33.

What is claimed is—

The combination with a support having 100 vertically open sockets and arms extending horizontally over the said sockets, of a table including uprights having their lower ends seated in said sockets and their intermediate portions connected with said arms, 105 angle plates carried by the upper ends of

the uprights, a table top pivotally connected to said angle plates, a tapering frame pivotally connected at its wider end to the uprights below said arms, and angle socket members carried by the lower face of the outer end of the table, and spaced inwardly of the sides thereof for receiving the narrower end of said tapering frame.

In testimony whereof, we affix our signatures, in the presence of two witnesses.

AMOS N. KNUTSON.

GEORGE H. HACKER, JR.
